(57) **CLAIM**

I claim the ornamental design for a deck chair, as shown.

DESCRIPTION

FIG. 1 is a perspective view of a deck chair showing my new design, the deck chair having the back portion in a folded position;

FIG. 2 is a front elevational view thereof;

FIG. 3 is a left side elevational view thereof;

FIG. 4 is a top plan view thereof;

FIG. 5 is a rear elevational view thereof; and,

FIG. 6 is a perspective view of the deck chair of FIG. 1 having the back chair in a reclined position.
